ATTORNEY.

UNITED STATES PATENT OFFICE.

CHARLES LEIB, OF PHILADELPHIA, PENNSYLVANIA.

DESIGN FOR A GARMENT-EYE.

SPECIFICATION forming part of Design No. 35,658, dated February 4, 1902.

Application filed December 21, 1900. Serial No. 40,697. Term of patent 14 years.

To all whom it may concern:

Be it known that I, CHARLES LEIB, a citizen of the United States, residing at Philadelphia, in the county of Philadelphia and State 5 of Pennsylvania, have invented and produced a new and original Design for a Garment-Eye, of which the following is a specification, reference being had to the drawings forming part thereof.

10 In the drawings, Figure 1 is a plan view of an eye of the class known to the trade as "hook and eye," and my design pertains to the new and useful design for an eye herein shown. Fig. 2 is a side view.

15 The leading or material feature of my design consists of the looped side pieces curved in the form approximately of an arc of a circle and converging toward each other, the inner ends of the two side pieces being substantially parallel to each other and being sepa-

rated from each other by a small distance and connected integrally with each other by a straight connecting member at approximately right angles to the inner ends of the curved converging looped side pieces. 25

22 are the curved converging looped side pieces, having at their outer ends the loops 33 and being connected together at their inner ends by the straight connecting member 1.

Having described my invention, what I 30 claim as new, and desire to secure by Letters Patent, is—

The design for a garment-eye, as herein shown and described.

In testimony whereof I affix my signature 35 in presence of two witnesses.

CHARLES LEIB.

Witnesses:

WILLIAM WEBSTER,
ALBERT L. TAYLOR.
